RECORDING AND MEASURING INSTRUMENT

James E. Bevins, Ramsey, and Robert W. Hyde, Englewood, N. J., assignors to Bendix Aviation Corporation, Teterboro, N. J., a corporation of Delaware

Original application April 16, 1945, Serial No. 588,600, now Patent No. 2,551,866, dated May 8, 1951. Divided and this application March 13, 1950, Serial No. 149,927

1 Claim. (Cl. 242—55)

This application is a division of application Serial No. 588,600, filed April 16, 1945, now Patent No. 2,551,866.

This invention relates to new and useful improvements in recording instruments of the type including a tape supply roll, and motor drive mechanism for unreeling the tape from the supply roll and drawing it through printing mechanism for effecting a visible record upon the tape. More particularly it is concerned with an irreversible slip clutch device in such drive mechanism, whereby the latter is effective to unreel the tape from the supply roll and carry it in only one direction.

A further feature of the invention is manually operable drive mechanism for effecting a slipping action of the clutch device and movement of the tape independently of the motor drive mechanism.

The foregoing and other objects and advantages of the invention will appear more fully hereinafter from a consideration of the detailed description which follows, taken together with the accompanying drawings wherein an embodiment of the invention is illustrated. It is to be expressly understood, however, that the drawings are for purposes of illustration and description only, and are not to be construed as defining the limits of the invention.

In the drawings, Fig. 1 is a front elevational view of the instrument with its cover removed;

Fig. 2 is a vertical section taken on the lines 2—2 of Fig. 1; and

Fig. 3 is a section of an irreversible slip clutch in the tape-drive gearing.

Referring now to the drawings wherein an instrument embodying the invention is disclosed, at the front of the instrument is a horizontally disposed roll 44 carrying a supply of record receiving chart or tape 35. The tape is threaded upwardly over an idle roller 121 (Fig. 2) and through suitable print effecting mechanism, generally designated 10, to a tape drive roller generally designated 56. The print mechanism includes suitable type or markers 66, an inked ribbon 49 intermediately of the markers and the tape, and a platen 67 disposed rearwardly of the tape and biased toward said tape by springs 68. The platen is operatively connected in suitable manner to a drive motor 45 so as to periodically move sharply against the tape to effect, through engagement of the tape with the ribbon, and the latter against the markers, a visible record or print mark upon the tape.

The tape is unreeled from the supply roll and drawn through the print mechanism by the drive roller 56. The latter carries at opposite ends pinwheel elements 124 and 133, the pins 122 of which engage successively in perforations, formed in the marginal edges of the tape, causing the latter to unreel from the supply roll as the drive roller rotates.

The supply roll 44 is slipped at one end on a stud 112 fixed in the framework 43 of the instrument. A friction drag is provided at the opposite end of the roll 70 by means of a spring 113 acting against a grooved hub 114 which turns with the tape supply roll, the hub being

2

rotatably mounted on a lever 115 which is pivotally mounted on a pin 116 held in the framework 43. Lever 115 is also connected with the framework by a tension spring 117 (Fig. 2) which biases lever 115 against a stop portion 118 of the framework. As shown in Fig. 1, screw adjustment means 119 is provided on the framework to insure horizontal alignment of the tape supply roll.

The tape drive roller 56 comprises a supporting shaft 123. The latter carries the hubs of the pinwheel members 124 and 133 at opposite ends and a plurality of spaced hubs 125 over which the tape is drawn as drive roller 56 rotates. The drive roller is driven at a constant speed by motor 45 which is connected by suitable motor speed control gearing 46, an irreversible slip clutch arrangement generally designated 75 (Fig. 3), and gearing 46' to the drive roller. The slip clutch permits the drive roller to turn in only one direction.

The slip clutch includes a driving gear member 11 which is operatively connected to gearing 46. Spring pawls 128 mounted on a face of slip clutch gear member 11 frictionally engage in ratchet recesses 129 formed in an opposed end face of a hub 127. The latter is engaged by gearing 46' with the tape drive roller 56, by which arrangement the latter is driveable in only one direction.

A knob 75 arranged at one end of the tape drive roller permits manual rotation of the latter independently of the motor drive. When the drive roller is driven manually through knob 75 at a speed exceeding its normal speed, this motion is transmitted through the gearing 46' to the hub gear member 127, whereby the ratchet recesses 129 in the end face of the latter are caused to successively slip from beneath the spring pawls 128 of the relatively slower rotating clutch drive gear 11.

Gearing 131 (Fig. 1) connects the tape drive roller 56 with two friction tape re-roller members 59 (Fig. 2), so that when drive roller 56 is rotated either manually or by motor drive, the re-rollers rotate at the same time with the drive roller. Spring guides or clips 58, secured to the framework by a lever 130, guide and hold the tape in a roll as it is being re-rolled by roller members 59.

While an embodiment of the invention has been illustrated and described in detail, it is to be expressly understood that the invention is not limited thereto. Various changes can be made in the design and arrangement of the parts without departing from the spirit and scope of the invention as the same will now be understood by those skilled in the art.

We claim:

In recording apparatus of the character described including at one end thereof a supply roll of marginally perforated record receiving tape of appreciable width, a rotatable shaft at the other end of the apparatus carrying pin wheel members engageable with the perforations of the tape for unreeling the latter uniformly from the supply roll and drawing it past intermediately positioned print means operable for printing a record on the tape, and driving mechanism for rotating the said shaft at a constant rate of speed including drive gearing connected with a power source; a slip clutch arrangement comprising a driving clutch gear operatively engaged by the drive gearing, a plurality of spring pawls carried by a face of this clutch gear, a driven clutch gear engaged with gearing carried by the rotatable shaft for driving the latter, the driven clutch gear having ratchet recesses in a face thereof in which recesses the said spring pawls are frictionally engaged, as a result of which slip clutch arrangement the driven clutch gear is driveable in only one direction by the driving clutch gear, and whereby the ratchet recesses in the face of the driven clutch gear are caused to be successively slipped from beneath the spring

3

pawls when the driven clutch member is caused to rotate at a speed exceeding that of the driving clutch gear, the rotatable shaft including means for rotating the same independently of the driving mechanism at a speed exceeding that of the driving clutch gear and effecting a consequent increased speed of the driven clutch gear to cause said slipping action.
